UNITED STATES PATENT OFFICE

FRIEDRICH WILHELM LÜLING, OF VOLMARSTEIN-ON-THE-RUHR, GERMANY

DESIGN FOR A PADLOCK

Application filed August 23, 1932, Serial No. 44,671, and in Germany July 13, 1932. Term of patent 14 years.

To all whom it may concern:

Be it known that I, FRIEDRICH WILHELM LÜLING, a citizen of the German Empire, residing at Volmarstein-on-the-Ruhr, Westphalia, Germany, have invented a new, original, and ornamental Design for Padlocks, of which the following is a specification, reference being had to the accompanying drawing, forming part thereof.

In the drawing:

Fig. 1 is a perspective front view of a padlock showing my new design,
Fig. 2 is a back view, and
Fig. 3 is a side view.

I claim:

The ornamental design for a padlock as shown.

FRIEDRICH WILHELM LÜLING.
